UNITED STATES PATENT OFFICE.

GILBERT J. SELLMEYER, OF INDIANAPOLIS, INDIANA.

AUTOMATIC CHANGEABLE EXHIBITOR.

1,368,061.

Specification of Letters Patent.

Patented Feb. 8, 1921.

Application filed April 16, 1919. Serial No. 228,919.

To all whom it may concern:

Be it known that I, GILBERT J. SELLMEYER, a citizen of the United States, residing at Indianapolis, in the county of Marion and 5 State of Indiana, have invented certain new and useful Improvements in Automatic Changeable Exhibitors, of which the following is a specification.

This invention relates to improvements in 10 changeable exhibitors and it is the principal object of the invention to provide an automatic exhibitor adapted for arrangement in public vehicles, stores or the like, for displaying, in sequential order and at 15 intermittent recurring intervals, a plurality of signs bearing suitable advertising matter, thus, providing an exceedingly attractive and novel device.

It is a more specific object of the invention 20 to provide a motor operated display device of the double reel and web type, provided with trip means whereby the signs arranged on the web will be moved into positions for display, in a step-by-step fashion and which 25 is capable of being reversed when the same has been wound about one of the reels, in order that it will be caused to travel in an opposite direction for winding about the remaining reel.

30 Another and equally important object of the invention is to provide the device with means for temporarily locking the sequentially displayed signs in positions for display whereby to positively prevent even 35 slight movement thereof, hence, facilitating the reading or observation of said signs.

Other objects will be in part obvious and in part pointed out hereinafter.

The invention accordingly consists in the 40 features of construction, combinations of elements and arrangement of parts which will be exemplified in the construction hereinafter set forth, and the scope of the application of which will be indicated in the following claims.

In the accompanying drawings, wherein is shown one of various possible embodiments of my invention:

Figure 1 is a vertical longitudinal section 50 through the exhibitor.

Fig. 2 is a horizontal section therethrough,

Fig. 3 is a fragmentary detail of the trip member.

Fig. 4 is a detail in perspective of the 55 locking means,

Fig. 5 is a fragmentary side elevation of the same,

Fig. 6 is a fragmentary detail in elevation of the reel and disk drive,

Fig. 7 is a detail in perspective of the 60 clutch rod and release, and

Fig. 8 is a fragmentary detail of the other disk and trip.

Having more particular reference to the drawing, in connection with which like reference characters will designate corresponding parts throughout the several views, the reference numerals 1 and 2 designate the several reels of the exhibitor, which as will be noted, have the opposite ends of a suitable web 3 engaged therewith and adapted to be alternately wound thereabout. The reel 1 is removably supported while the reel 2 is permanently supported in bearings generally indicated by the numeral 4 arranged in the casing 5 of the exhibitor; certain of said bearings having beveled gears 6 fixedly mounted upon the outer extremities of their respective shafts, which gears in turn, mesh with similar gears 7 splined to the opposite 70 ends of a vertically disposed driven shaft 8. In this connection, it is to be noted that the hub portions or collars of the several beveled gears 7 have their inner portions serrated as at 9, thus providing clutch elements, which 75 are adapted to be alternately engaged by connecting pins 10 passing through the adjacent portions of said shaft 8.

80 A power transmission or driving shaft 11 is disposed at substantially right angles to the intermediate portion of the vertical shaft 8 and carries a bevel gear 12 upon one end thereof meshing with a similar gear 13 engaged with the drive shaft of a suitable form of motor 15 which as will be understood, may be either of electric, spring or weight operated types. It will be noted that said gear 13 is formed with a blank portion 13' for a purpose to be hereinafter described. Also mounted on the drive shaft of the motor 15 is a disk 14 having a trip arm 16 adjustably connected thereto as at 17; the outer end of the trip being formed concave as at 18, for a purpose which will be hereinafter 85 more fully described. A second bevel gear 19 is loosely mounted on the remaining end of the driving shaft 11 and has a clutch element 20 formed upon its inner side, which clutch element is adapted to be engaged by a movable clutch element 21 splined to the 90

100 motor 15. Figure 2 is a horizontal section through the exhibitor showing the arrangement of the various parts. Figure 3 is a fragmentary detail of the trip member 16 showing the manner of adjustment of the same. Figure 4 is a detail in perspective of the locking means. Figure 5 is a fragmentary side elevation of the exhibitor showing the reels 1 and 2 and the web 3. Figure 6 is a fragmentary detail in elevation of the reel 1 and the disk 14. Figure 7 is a detail in perspective of the clutch rod and release. Figure 8 is a fragmentary detail of the other disk and trip member.

shaft 11 and having a yoke 22 loosely engaged with the collar thereof which yoke is provided with a laterally extending operating rod 23 having a notch or keeper 24 formed therein intermediate its ends and a roller 25 mounted in its free end adapted to be engaged with the concaved end 18 of the trip arm 16 at times. This gear 19 meshes with a bevel gear 26 suitably splined to the intermediate portion of the vertical shaft 8 which latter freely slides through said gear and as will be understood, this gear 26 meshes with the gear 19 irrespective of the shifting or other movement of said shaft 8.

15 Mounted in suitable bearings arranged in the casing 5 is a screw threaded shaft 27 having a collar 28 engaged therewith, which collar carries a pivoted trip arm 29. Mounted on one end of the screw threaded shaft is a pinion 30 meshing with a second but larger pinion 31 carried by the bevel gear 6 arranged on the reel 2. Thus, it will be appreciated that upon rotation of the reel 2, rotary motion will be imparted by way of the gears 30 and 31 to the screw threaded shaft 27. A bevel gear 32 is mounted on one portion of the screw threaded shaft 27 in proximity to the pinion 30 and meshes with a compound gear 33, which gear in turn 30 meshes with the gear teeth 34 arranged upon the peripheral surface of a rotatable disk 35. Extending longitudinally of the upper reel 2 and arranged in parallel relation to the screw threaded shaft 27 is a trip rod 36 carrying dogs 37 upon the opposite portions thereof, while one end of said rod is pivotally connected to a bell crank lever 38 pivotally mounted as at 39 in the housing 5 and having connection with a link 40, which link is 40 in turn connected to a collar 41 fixedly mounted on the vertical shaft 8. Other trip rods 42 and 43 are arranged below the rod 36 and in parallel relation to the screw threaded shaft 27; these rods carrying dogs 44 and 45 45 upon the opposite extremities thereof, while the adjacent ends of the same are pivotally engaged with bell crank levers 46 having connection with links 47, the lower ends of which are secured to an operating rod 48 carrying 50 a roller 49 upon its outer or free end. As will be noted, this roller 49 is disposed in the path of travel of the trip arm 16, for a purpose which will be hereinafter described.

55 Spaced series of circumferentially disposed cams designated by the numerals 50 and 51 are arranged on one face of the disk 35 and as will be noted, oppose each other, while in the outer portion of said disk, a plurality of pairs of circumferentially disposed 60 openings 52 are formed.

Pivottally mounted adjacent one side of the rod 23 is a catch lever 53 adapted to be engaged, at times, in the keeper or notch 24 formed in said rod; said catch lever being 65 normally placed under tension by means of a

coil spring 53' engaged with the pivot thereof and bearing on the same. A pivoted trip 54 is carried by the operating rod 23 and as will be noted, is adapted to be engaged with a trip which will be presently described. 70 Slidably mounted in proximity to the free portion of the lever 53 is a horizontally disposed trip element 55, said trip element being composed of a plurality of pivotally connected sections, certain of which, namely, the 75 outermost, is formed with a shoulder 56 adapted to be engaged, at times, with the free end of said catch lever 53 for moving the same in a direction to cause disengagement thereof from the keeper 24 in the rod 23. As 80 will be noted, the lower portion of the trip element 55 is bifurcated as at 57 and has rollers 58 and 59 rotatably mounted upon the lower ends thereof, which rollers are disposed for engagement with the circumferentially disposed series of opposed cams 50 and 51. In this connection, it is to be noted that the section of the bifurcated end carrying the roller 58 is pivoted to swing in one direction, while the section of the remaining 85 side of the bifurcated end which carries the roller 59 is pivoted to swing in an opposite direction. As a consequence, during rotary motion of the disk 35 and the engagement of the rollers with the various cams of the 90 several circumferentially disposed series, one side of the bifurcated extremity will be rendered substantially rigid, while the remaining side will be permitted to swing upon its pivot as indicated in the Fig. 3, thus allowing the particular roller carried thereby to be moved freely over the various cams of its respective or adjacent series. However, when rotation of the disk 35 is reversed, the 95 action of the pivoted bifurcated extremities 100 will be also reversed, thus permitting uninterrupted rotation of said disk and proper functioning of the trip 55.

As means for locking the disk 35 in its temporarily adjusted positions, to prevent 110 undue movement of the web 3 or the reels 1 and 2, I provide a horizontally arranged slidable locking pin 60 having a head 61 formed on its inner end, which head is adapted to be engaged by one portion or extremity of a bell crank lever 62 also pivotally mounted in the casing at a point in proximity to said pin. The remaining end of the lever 62 is pivotally connected to a link 63 extending into engagement with a second bell crank lever 64 also pivotally mounted upon suitable means in the casing and having its free end arranged in proximity to a catch 65 which is carried by the operating rod 23. To normally maintain the pin 60 in its locking position, a coil spring 66 is arranged thereabout and has one end of the same connected to said pin while the remaining end thereof is connected to one of the bearings therefor. Consequently, when the locking 120 125 130

pin is released, it will immediately move into engagement with the disk 35 and when one of the pairs of openings 52 is alined therewith, it will immediately enter the same.

5 In operation, the web is fully wound about one of the reels and the motor 15 is started. Rotary motion will be transmitted to the driving shaft 11 and to the disk 14 and as a consequence, when the trip arm 16 carried by said disk is engaged with the roller 25 on the adjacent end of the clutch operating rod 23, the movable clutch element 21 will be moved into engagement with the clutch element arranged on the gear 19, 15 designated 20, thus causing rotation of said gear and as a consequence, imparting rotary movement to the shaft 8, which in turn causes rotation of the reels 1 and 2, thus effecting the movement of the web 3 from 20 one reel onto the other. Such movement of the web will bring a particular sign into displaying position, adjacent the transparent pane arranged in the housing 5, whereupon the spring clutch catch lever 53 will engage 25 in the keeper 24 of said operating rod 23, thereby maintaining the clutch element 21 in engagement with the clutch element 20 for a period of time. Movement of the rod 23 to cause engaging of the clutch element 30 21 with the element 20 will also cause the bell crank lever 64 to be tripped by the catch 65 and as a consequence, the slideable locking pin 60 will be disengaged from one of the openings 52 in the rotatable disk 35, 35 thus allowing said disk to be rotated by reason of its connection with the reel 2. Upon rotation of the disk 35, the rollers 58 and 59 carried upon the bifurcated lower end of the trip 55 will engage with their respective series of cams and as a consequence, will cause said trip to slide and when the rollers have reached the highest point of the active series of cams, the shoulder 56 will engage with the free portion of the catch 40 45 lever 53 and move the same to cause disengagement thereof from the keeper 24 in the operating rod 23, thereby permitting the clutch element 21 to be immediately disengaged from the element 20 and as a consequence, interrupting the transmission of 50 rotary motion to the reels 1 and 2. As the roller engaged with the active series of cams becomes disengaged from the adjacent cam, the catch lever 53 is permitted to return to 55 its normal position ready for further engagement with the rod 23 when the same is again moved due to connection between the trip arm 16 and the roller 25 carried on the outer end thereof. In this way, it will be 60 65 understood that the disk 34 when engaged by the locking pin 60 will serve to positively prevent undue movement or travel of the web portion 3 and in this way will permit the sign alined with the transparent pane 65 in the housing to be properly displayed.

Rotation of the reels 1 and 2 in this step-by-step fashion continues until the web has been entirely removed from one and arranged about the other. At this time, the rotating screw threaded shaft 27 will have 70 caused the collar 28 to assume a position in proximity to the dogs 37 and 45 arranged on the trip rods 36 and 43. Hence, when the roller 49 is engaged by the trip arm 16, a pull will be imparted to the rod 43 by way 75 of the connecting rod 48, the bell crank lever 46 and link 47, thereby engaging the dog 45 with the adjacent end of the pivoted arm 29 and swinging the same in a direction to cause the free end of said arm to be swung 80 into engagement with the adjacent dog 37 on the trip rod 36. In this connection it is to be noted that the blank portion 13' of the gear 13 will cause motion thereto to be interrupted when the arm 16 engages the 85 roller 25 thus momentarily stopping the shaft 11 and clutch 21, permitting the same to be properly engaged with the clutch 20 and thereby avoiding the stripping of the teeth from each of the same. Such engagement of the free end of the arm 29 with said dog 37 will impart a pull to the rod 36, which in turn, will be transmitted to the vertical shaft 8, causing the shifting of the shaft to effect the disengagement of the pin 90 10 from the previously engaged gear 7 and the engagement of the remaining pin 10 with the adjacent gear 7, said connection, of course being effected by means of the clutch element 9 formed thereon. By so shifting 100 the vertically disposed shaft, the transmission of rotary motion to the reels 1 and 2 will be reversed and consequently, the web which is now arranged about the second reel will be caused to move therefrom onto said 105 first reel at this time, the reversing operation will be repeated should the operation of the motor 14 be continued. It is to be understood, that the reversing of the shaft 8 will also be effected when the collar 28 has 110 been returned to the opposite end of the screw threaded shaft 27, that is, that end carrying the bevel gear 32. However, at this time, the pivotal arm 29 will act upon the adjacent dog 37 and the dog 44 to effect 115 the reversal of rotary motion to the reels 1 and 2. Furthermore, when the direction of rotation of the reels is reversed, the direction of travel of the disk 35 will be also reversed and as a consequence, the formerly 120 inactive series of cams will become active, while the active ones will become inactive, thereby effecting the necessary movement of the trip 55 with relation to the catch lever 53.

125 It is to be understood, that to start the exhibitor, the roll 1 is placed in the casing by depressing one of the bearing elements 4, the remaining end then being engaged by the adjacent bearing 4, whereupon the free end of 130

the web is pulled upwardly and engaged with the reel 2 which has been previously mounted in its respective bearings 4 in the casing. The reel 2 is now rotated by hand 5 until the first sign alines with the transparent insert in the casing. At this time, the reel 1 is in proper position for feeding the sign carrying web therefrom. Hence, when the machine is automatically operated by 10 means of the motor 14, the signs will be properly alined with the transparent pane of the casing when displayed in sequential order.

From the foregoing, it will be understood by persons skilled in the art that I have provided an exceedingly attractive and efficient 15 changeable exhibitor which may be adapted for various uses, such as displaying advertising matter, or for displaying stations in railway or street cars, or in fact, in any instances 20 wherein it is desired to provide a novel form of changeable exhibitor. Further, the operation of the exhibitor is such as will permit the device to operate continuously with but little if any attention, thereby adding materially to the practicability of the same.

25 Manifestly, the construction shown is capable of considerable modification and such modification as is within the scope of my claims, I consider within the spirit of my invention.

I claim:

1. In an exhibitor of the character described, a motor, a driven shaft operated by said motor, a counter-shaft, disposed at right angles to the driven shaft and rotatably supported meshing gears connecting the driven and counter-shafts, the gear on the counter-shaft being mounted for the sliding of the latter, the gear on the driven shaft being 35 loose thereon, means for making fast the gear on the driven shaft, reel operating gears adapted to be alternately connected with the counter-shaft, and trip mechanism controlled by the operation of the motor to intermittently shift the counter-shaft and the means for making fast the gear on the driven shaft.
2. In an exhibitor of the character described, a motor having a mutilated driving gear, a disk rotatable with the driving gear, 40 a driven shaft having a pinion meshing with the driving gear, a counter-shaft disposed at right angles to the driven shaft and constructed and arranged for sliding and rotary movements, gear connections between the driving and counter-shafts, the gear on the driven shaft being loose thereon, a clutch on the driven shaft for engagement with the loose gear to make the same fast upon said driven shaft, a cam member rotatably supported, means for shifting the clutch, tripping means carried by the disk for intermittently moving the shifting means for the clutch, devices, one operated by the cam member to release the clutch shifting means,
3. In an exhibitor of the character described, a motor having a mutilated driving gear, a disk rotatable with the driving gear, 45 a driven shaft having a pinion meshing with the driving gear, a counter-shaft disposed at right angles to the driven shaft and constructed and arranged for sliding and rotary movements, gear connections between the driving and counter-shafts, the gear on the driven shaft being loose thereon, a clutch on the driven shaft for engagement with the loose gear to make the same fast upon said driven shaft, a cam member rotatably supported, means for shifting the clutch, tripping means carried by the disk for intermittently moving the shifting means for the clutch, devices, one operated by the cam member to release the clutch shifting means,

and the other operated by said shifting means to control the movement of the cam member and tripping mechanism for shifting the counter-shaft and controlled by the tripping means on the disk.

3. In an exhibitor of the character described, a motor having a mutilated driving gear, a disk rotatable with the driving gear, a driven shaft having a pinion meshing with the driving gear, a counter-shaft disposed at right angles to the driven shaft and constructed and arranged for sliding and rotary movements, gear connections between the driving and counter-shafts, the gear on the driven shaft being loose thereon, a clutch on the driven shaft for engagement with the loose gear to make the same fast upon said driven shaft, a cam member rotatably supported, means for shifting the clutch, tripping means carried by the disk for intermittently moving the shifting means for the clutch, devices, one operated by the cam member to release the clutch shifting means, and the other operated by said shifting means to control the movement of the cam member, and tripping mechanism for shifting the counter-shaft and controlled by the tripping means on the disk, and reel operating mechanism positively engaged alternately by the counter-shaft for transmitting motion from the motor thereto.

4. In an exhibitor of the character described, a motor having a mutilated driving gear, a disk rotatable with the driving gear, a driven shaft having a pinion meshing with the driving gear, a counter-shaft disposed at right angles to the driven shaft and constructed and arranged for sliding and rotary movements, gear connections between the driving and counter-shafts, the gear on the driven shaft being loose thereon, a clutch on the driven shaft for engagement with the loose gear to make the same fast upon said driven shaft, a cam member rotatably supported, means for shifting the clutch, tripping means carried by the disk for intermittently moving the shifting means for the clutch, devices, one operated by the cam member to release the clutch shifting means, and the other operated by said shifting means to control the movement of the cam member, and tripping mechanism controlled by the tripping arm to shift the counter-shaft, reel operating mechanism alternately engaged positively by the counter-shaft, and tripping mechanism actuated by the tripping arm to effect the reversal of movement of the cam member and also the operating mechanism for reels.

In testimony whereof, I affix my signature hereto.

GILBERT J. SELLMEYER.
